UNITED STATES PATENT OFFICE.

FREDERIC C. SMITH, OF WATERBURY, CONNECTICUT, ASSIGNOR TO WATERBURY MFG. CO., OF WATERBURY, CONNECTICUT, A CORPORATION.

DESIGN FOR A VACUUM WATER-BOTTLE.

51,002.

Specification for Design.

Patented July 3, 1917.

Application filed April 13, 1917. Serial No. 161,913. Term of patent 14 years.

To all whom it may concern:

Be it known that I, FREDERIC C. SMITH, a citizen of the United States, residing at Waterbury, in the county of New Haven and State of Connecticut, have invented a new, original, and ornamental Design for a Vacuum Water-Bottle, of which the following is a specification, reference being had to the accompanying drawing, forming part thereof.

The figure is a side elevation of a vacuum water bottle, showing my new design.

I claim:

The ornamental design for a vacuum water bottle, as shown.

FREDERIC C. SMITH.
